Primary Examiner — Elizabeth J Oswecki*Assistant Examiner* — Lacey Chey Bowman(74) *Attorney, Agent, or Firm* — Bayramoglu Law Offices LLC(57) **CLAIM**

The ornamental design for an internet protocol camera, as shown and described.

DESCRIPTION

FIG. 1 is a front perspective view of an internet protocol camera showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The even broken lines shown in the drawings are included for the purpose of illustrating portions of the internet protocol camera that form no part of the claimed design.

1 Claim, 8 Drawing Sheets(56)
